J. A. SHARP,
BINDING MECHANISM FOR GRAIN BINDERS,
APPLICATION FILED OCT. 30, 1915.

1,261,860.

Patented Apr. 9, 1918.

Inventor.
James A. Sharp,
By *Mr. E. L. M.*
Atty.

UNITED STATES PATENT OFFICE.

JAMES A. SHARP, OF SPRINGFIELD, OHIO, ASSIGNOR TO INTERNATIONAL HARVESTER COMPANY OF NEW JERSEY, A CORPORATION OF NEW JERSEY.

BINDING MECHANISM FOR GRAIN-BINDERS.

1,261,860.

Specification of Letters Patent.

Patented Apr. 9, 1918.

Application filed October 30, 1915. Serial No. 58,782.

To all whom it may concern:

Be it known that I, JAMES A. SHARP, a citizen of the United States, residing at Springfield, in the county of Clark and State of Ohio, have invented certain new and useful Improvements in Binding Mechanisms for Grain-Binders, of which the following is a full, clear, and exact specification.

10 My invention relates to binding mechanisms for grain binders.

It has for its object to improve the binding mechanism of a grain binder, and especially the tripping and compressing device thereof, in such a manner that an improved bundle is formed and the tension may be very conveniently adjusted. I attain these objects by an improved construction wherein the clutch dog stop, connected 15 to the compressor trip, is connected to the cam gear through improved resilient connections comprising a plurality of springs, the tension of which is adjustable by improved means hereinafter more specifically 20 described.

25 In the accompanying drawings I have, for purposes of illustration, shown one embodiment which my invention may assume in practice.

30 In these drawings:

Figure 1 is a partial side elevation of a binder mechanism equipped with my improvement.

Fig. 2 is a detail view of the spring mechanism.

Fig. 3 is a partial sectional view taken on line 3—3 of Fig. 2.

Fig. 4 is a detail view of the threaded member and slidable spring abutment interlocked therewith.

40 The binder shown is of standard construction comprising a binder frame 1 disposed adjacent the deck 2, the binding mechanism thereof, not shown, being controlled by a 45 rotatable clutch dog 3 which is in turn controlled by a stop member 4. This stop is pivoted upon a shaft 5 which carries a compressor trip 6, the latter extending upward into the path of the grain passing over the 50 deck 2 in a well known manner. As in the usual construction, a crank 7 on the needle shaft is also connected through a trip rod or link 8 with a rotatable cam wheel 9, and a cam wheel bell crank 10, pivoted at 11, 55 engages with a cam surface 12 of the cam

wheel 9, this bell crank being connected to the stop member 4 by means of a rod 13 pivoted to the stop and slidably connected to a spring case 14 pivoted to the bell crank.

In my improved construction, a plurality 60 of springs 15 and 16 are carried upon the upper or free end of the rod 13, which is inclosed within the case, the spring 15 being of heavy material, while the spring 16 is relatively lighter. As shown, a slotted 65 abutment 17 is threaded upon the free end of the rod 13 and this abutment, which acts as the upper limit for the spring 15, is slid- 70 able in ways 18 formed on the sides of the case at the upper end thereof. An intermediate slotted abutment 19 is also disposed between the two springs 15 and 16 and like- 75 wise slidable with respect to the case, this abutment, however, being limited in its movement by engagement with oppositely 80 extending lugs 20 formed on opposite sides of the case. Attention is also directed to the fact that a third or bottom slotted abutment 21 is also provided for the light spring 16, this abutment also being movable along 85 ways 22 similar to the ways 18 but located in this instance between the lugs 20 and the lower end of the case.

Threaded in the opening in the lower end 90 of the case, through which the rod 13 passes 85 (indicated at 23 in Fig. 3), is a threaded tubular member 24 which acts as a bushing for the rod 13. This threaded member is preferably provided with a nut-like end 25 so that it may be readily turned, and is ad- 90 justable longitudinally of the case 14. This member is also provided with a flanged or table-like top 26 having thereon a pair of oppositely disposed upstanding rounded pro- 95 jections or knobs 27 thereon which are receivable in the slots formed in the abutment 21 at points inside the inner edges of the ways 22. (Fig. 3.)

In the operation of the binder the lower 100 or light spring 16 acts as the trip spring and also as a means for bringing the binder home, while the upper or heavy spring acts as the compression spring. Obviously, any desired tension adjustment of the spring 16 may be made by rotating the threaded mem- 105 ber 24, the latter in its rotating movement carrying the projections or knobs 27 around under the abutment 21 and causing the latter to be raised and the parts being located definitely in position at each half turn by 110

the seating of these projections or knobs 27 in the slots in the abutment 21. Due to this construction, it will be noted that the adjustment of the spring tension or the size 5 of the bundle may be very readily made without in any way disconnecting any of the spring mechanism or adjusting any parts which are inaccessible, the only part requiring adjustment being the threaded 10 member 24 which is readily accessible.

While I have in this application specifically described one embodiment which my invention may assume in practice, it is, of course, to be understood that my invention 15 is not limited to the specific form shown herein, but may be modified to assume other forms without departing from its spirit, it being my intention to include all such forms of the invention within the scope of the ap- 20 pended claims.

What I claim as my invention and desire to secure by Letters Patent is:

1. In combination, a case, a rod slidable therein, a plurality of springs carried by 25 said rod and within said case, and an abutment carried by said rod between adjacent springs and slidable with respect to said rod and on said case.

2. In combination, a case, a rod slidable 30 therein, a plurality of springs of different tension carried by said rod within said case, and an abutment carried by said rod between adjacent springs and slidable with respect to said rod and on said case.

3. In combination, a spring case, a trip 35 rod slidable therein, springs of different strength coiled about said rod within said case, and means slidably receiving said rod and operable from the exterior of said case 40 for adjusting the spring tension.

4. In combination, a spring case, a trip rod slidable therein, a plurality of springs coiled about said rod, a rotatable member carried by said case having a bore through 45 which said rod is slidable, means whereby the tension of one of said springs may be adjusted by manipulation of said member, and an abutment located on said rod between two of the springs, and slidable with 50 respect to said rod and on said casing.

5. In combination, a spring case, a trip rod slidable therein, spring mechanism on said rod and within said case, an adjustable member carried by said case and adjustable

relative thereto through which said rod is 55 reciprocable, and a spring abutment held against rotation by said case, one of said last mentioned elements having a projection on its face while the other has a recess in which said projection is receivable. 60

6. In combination, a spring case, a trip rod slidable therein, spring mechanism surrounding said rod and disposed within said case, a spring abutment on said rod and held against rotation by said case, a member hav- 65 ing interlocking means threaded into said case having a bore through which said rod is slidable, said abutment and said threaded member releasable when the latter is rotated.

7. In combination, a case, a rod slidable 70 therein, an abutment on the upper end of said rod, a slidable abutment intermediate said first named abutment and the lower end of said case, a spring mounted on said rod on each side of said slidable abutment, and 75 means for limiting the downward movement of said slidable abutment.

8. In combination, a case, guideways formed thereon, a rod slidable therein, an adjustable abutment on the upper end of 80 said rod, a slidable abutment carried on said case and slidable on said guideways intermediate the upper end of said rod and the lower end of said case, a spring mounted on said rod on each side of said slidable 85 abutment, and means for limiting the downward movement of said slidable abutment.

9. In combination, a case, a rod slidable 90 therein, an abutment on the other end of said rod, a slidable abutment mounted on said rod intermediate the upper end of the same and the lower end of said case, a spring mounted on said rod on each side of said slidable abutment, and means for adjusting the tension of said springs. 95

10. In combination, a case, a rod slidable therein, an abutment on the upper end of said rod, a slidable abutment intermediate the upper end of said rod and the lower end of said case, a spring mounted on said rod on each side of said slidable abutment, means for limiting the downward movement of said slidable abutment, and means threaded into said case for adjusting the tension of said springs. 100

In testimony whereof I affix my signature.

JAMES A. SHARP.
